Kenyon & Kenyon.

UNITED STATES PATENT OFFICE.

EDGAR C. BEECROFT, OF PELHAM MANOR, NEW YORK.

CRUTCH.

1,401,305.

Specification of Letters Patent.

Patented Dec. 27, 1921.

Application filed March 10, 1919. Serial No. 281,699.

To all whom it may concern:

Be it known that I, EDGAR C. BEECROFT, a citizen of the United States, residing in Pelham Manor, county of Westchester, State 5 of New York, have invented certain new and useful Improvements in Crutches, of which the following is a specification.

My invention relates to crutches and more particularly to a cushion for the upper end 10 of a crutch to serve as a comfortable rest for the arm of the user. One of the objects of the invention is to provide improved means whereby the cushion may be easily and securely fastened to an ordinary crutch 15 without necessitating any changes in the structure of the parts of the crutch associated therewith. Further objects, features and advantages of the invention will appear more fully from the following description 20 taken in connection with the accompanying drawing forming a part of this specification and illustrating one embodiment of the invention.

In the drawing, Figure 1 is a side elevation 25 showing my invention applied to the upper end of a crutch. Fig. 2 is a central vertical longitudinal sectional view of the same form of invention applied to the upper end of a crutch, the crutch being shown 30 in side elevation. Fig. 3 is a cross-section taken on line 3—3 of Fig. 2.

Referring to the drawing the numeral 1 represents the arm rest at the upper end of 35 a crutch, this rest being of usual shape and construction and being secured to the upper end of the upright members 2 and 3 of the crutch.

The cushion shown has an elongated inflatable body 4, provided at one end with a 40 hollow neck 5, to the outer end of which is secured an inflating valve 6. This valve may be of any suitable construction; and as such valves are well-known in the art a detailed description thereof is thought unnecessary. The body portion 4 of the cushion 45 is curved longitudinally so as to be adapted to rest closely against the upper curved surface of the rest 1 of the crutch, the length thereof being desirably sufficient 50 to permit the same to extend from one end to the other of the said arm rest and to enable the neck 5 to be folded about one end of the said part 1, whereby the valve 6 may be positioned under the said part. Trans- 55 versely the body 4 is made of suitable curved

shape so that the arm of the user may rest comfortably thereon. The cushion may be of suitable air-tight flexible material such as rubber or leather.

In order to hold the cushion firmly in place upon the crutch, I have shown securing means extending substantially throughout the entire length of the crutch. The means shown comprises a lacing 7 connected to the outer edges of flaps 8 and 9, which extend 60 from the body of the cushion, and are adapted to engage opposite sides of the part 1 of the crutch. The lacing as shown extends back and forth under the said part 1 substantially from one end of the cushion to the 65 other and at one end passes under the valve 6 to hold the latter firmly against the part 1 of the crutch. The lacing as shown extends on opposite sides of the parts 2 and 3 of the crutch and thereby effectively prevents longitudinal movement of the cushion. In order to prevent the cushion from slipping over the top of the crutch in a direction at right angles to the length of the cushion, the flaps 8 and 9 which are desirably made of the same material as the body 70 of the cushion and may be integral therewith are provided with suitable stiffening means. These means as shown comprise two plates 75 10 and 11 arranged respectively upon the inner faces of the flaps 8 and 9. These plates extend, as shown in dotted lines in Fig. 1, substantially from one end of the flaps to the other, and as shown in Fig. 3, are slightly embedded within the material 80 of the flaps. The plates 10 and 11 also tend to prevent buckling of the cushion from the ends toward the middle. Referring to Fig. 3 the eyelets 12 through which the lacing 85 7 passes, extend through and connect the plates 10 and 11 with the corresponding flaps, the said plates serving to re-inforce the flaps and to prevent the eyelets from being torn by the lacing through the material of the flaps. The plates 10 and 11 are desirably thin sheets of metal.

It will be seen that the cushion described above may readily be attached to the ordinary form of crutch or detached therefrom. When fastened in position the cushion will 105 remain in proper relation to the upper end of the crutch. While a pneumatic cushion has been shown, many of the features of my invention are applicable to cushions of other types. My invention is susceptible of a va- 110

riety of modifications, and it is to be understood that I do not limit my invention to the details here shown and described, except as expressed in any given claim.

5 Having described my invention, what I claim as new and desire to secure Letters Patent for is:

10 1. The combination with an elongated pneumatic cushion having an inflating valve connected at one end thereof, by a connection adapted to be folded about one end of the rest at the upper end of a crutch, of means for detachably securing said cushion to the rest with the valved end of the cushion 15 folded about one end of the rest and the valve held in place under the rest.

20 2. The combination with an elongated pneumatic cushion having an inflating valve connected by a hollow neck to one end thereof, of means for detachably securing said cushion to the rest at the upper end of a crutch with the neck folded about one end of the rest and the valve held in place under

the rest, said means comprising flaps and a lacing therefor.

25

3. The combination with a cushion having flaps adapted to engage opposite sides of the crutch, of means coacting with said flaps to fasten the cushion to the upper end of the crutch, said flaps carrying stiffening means 30 to prevent the cushion from being displaced on the crutch transversely to the length of the cushion.

4. The combination with a cushion having flaps adapted to engage opposite sides 35 of the crutch, of means coacting with said flaps to fasten the cushion to the upper end of the crutch, said flaps carrying stiffening plates to prevent the cushion from longitudinal buckling and from being displaced on 40 the crutch transversely to the length of the cushion.

In testimony wherof, I have signed my name to this specification.

EDGAR C. BEECROFT.
